(57) **CLAIM**

The ornamental design for a dental curing light, as shown and described.

DESCRIPTION

FIG. 1 is an upper perspective view of a dental curing light showing our new design;

FIG. 2 is an upper perspective view thereof that is enlarged relative to FIG. 1;

FIG. 3 is an enlarged upper perspective view thereof;

FIG. 4 is a lower perspective view thereof; and,

FIG. 5 is a cross-sectional view thereof taken along line 5-5 of FIG. 4.

The broken lines immediately adjacent the shaded areas represent the bounds of the claimed design, while all other broken lines are directed to environment and are for illustrative purposes only; the broken lines form no part of the claimed design.

1 Claim, 5 Drawing Sheets
